UNITED STATES PATENT OFFICE.

BURT D. STEVENS, OF EVANSTON, ILLINOIS, ASSIGNOR TO MIEHLE PRINTING PRESS AND MANUFACTURING COMPANY, OF CHICAGO, ILLINOIS, A CORPORATION OF ILLINOIS.

PRINTING-PRESS SHEET-TRANSPORTING MECHANISM.

Application filed March 3, 1921. Serial No. 449,527.

The manner of feeding paper sheets to the impression-cylinders of printing-presses of the stop-cylinder type and their delivery from such cylinders forms the subject-matter 5 of the present invention, the salient or outstanding characteristic of the latter being the initiation of the delivery of the printed sheet from the cylinder before the latter stops or becomes stationary and the feeding 10 of the next unprinted sheet to such cylinder during such period of dwell or rest.

A further feature of the invention resides in not only having the delivery grippers or fingers or corresponding elements take the 15 sheets from the cylinder while the latter is revolving, thus permitting the sheet to be stripped or removed from the cylinder more easily than could be accomplished if the cylinder were still, but also to have such 20 grippers or fingers momentarily travel at a slower speed than that of the cylinder when they first act on the sheet, thus to some extent buckling the sheet back on the cylinder, rendering it more readily stripped or drawn 25 from the latter, than would occur were the two elements traveling at the same speed, or were the cylinder revolving more slowly than the travel of the delivery members.

In the particular appliance described in 30 detail in this application, at the time the removal of the sheet from the cylinder is instituted, the rotation of the latter is being progressively retarded, and the travel of the delivery fingers or grippers is accelerating, 35 but, nevertheless, the cylinder at the instant of the sheet transfer is traveling faster than the delivery gripper fingers, thereby producing the desired buckling or curling of the sheet away from the cylinder to facilitate its 40 removal from the latter.

Another feature of the invention is the 45 rocking of the delivery gripper mechanism on its oscillatory support whereby it is always in correct position either to receive or discard a sheet, as the case may be. In other words, the change of position which would otherwise occur in the gripper mechanism by reason of the movements of its mounting are compensated for.

50 In the accompanying drawings I have illustrated one desirable embodiment of the invention, the same reference characters re-

ferring to like parts throughout the several views, but it is to be understood that the invention is susceptible of a number of satisfactory embodiments varying more or less in mechanical details but all incorporating the main or underlying principles of construction and mode of operation constituting the heart and essence of the invention.

In these drawings, to which reference should be made in connection with the following detailed description of the construction and manner of functioning of the appliance:

Figure 1 is a substantially-central, vertical, lengthwise section through the printing-press, illustrating in full lines the positions of the delivery device and the impression-cylinder at practically the moment when the transfer of the sheet from the latter to the former occurs during the retarded portion of the rotation of the cylinder preliminary to its becoming stationary;

Figure 2 is an enlarged, fragmentary, detailed section showing the positions of the parts just previous to the establishment of the delivery of the printed sheets;

Figure 3 depicts the relation of the same elements after the delivery has been inaugurated;

Figure 4 is a partial plan view of the parts shown in Figure 2 with spring 53 omitted;

Figure 5 indicates the delivery appliance 85 just after having released the printed sheet which has been transported over the printed sheet pile;

Figure 6 is a fragmentary detail view; and 90

Figure 7 is a side elevation of a portion of the driving mechanism; and

Figure 8 shows in fragmentary manner the way of coupling the impression-cylinder to its driving-gear and disconnecting it therefrom.

Turning to these drawings, it will be found that the printing-press includes a main-frame 11 supplied with a suitably-guided, vertical, sliding bed 12 carrying the printing-form, not shown, and reciprocated in approved fashion at a somewhat varying speed by a counterbalanced crank-shaft 13 in the base of the machine revolved by any source of power, not illustrated, and opera-

tively associated with the bed through a crank-arm 14, a connecting-rod 15, gears 16, and stationary and movable racks 17 and 18, respectively, such driving connection constituting the subject-matter of a companion co-pending patent application Serial No. 451,707, filed March 12, 1921.

A "stop" impression-cylinder 19 cut away on one side as shown in Figures 1 to 3 inclusive, is operated intermittently, being revolved always in the same direction at intervals, by a rack and gear and clutch connection with the reciprocating bed in the usual or any appropriate manner, the cylinder being supplied with gripper fingers 40 swung back and forth or opened and closed in the well-known manner.

To effect this movement of the cylinder, it is supplied with a coaxial, apertured driving-gear 101 to which the cylinder may be operatively connected in a well-known manner by a rod 102 slidably mounted in the cylinder and adapted to be projected into an aperture 103 of the gear, under which conditions, the gear rotates the cylinder, the gear being always in mesh with the teeth of a rack 104 on the vertically sliding bed.

Rod 102 has two collars 105, 106 fixed thereto and receives between them the forked or bifurcated end of an arm 107 pinned to an axially-disposed shaft 108 extending out through a bearing in the end wall of the cylinder and on which, if desired, the gear may be mounted.

The exposed end of this central, intermittently-rotating, clutch-operating shaft carries a relatively-stationary collar 109 between a pair of collars 110 and 111 pinned to the shaft, collar 109 having an arcuate slot 112 receiving a cam portion of a rock-arm 113 fulcrumed on the frame at 114 and oscillated by a cam 115 on shaft 13 and connecting bell-cranks and links 116, 117, 118 and 119.

When cam 115 causes the cam of arm 113 to push shaft 108 inwardly of the cylinder, then the drive-gear is uncoupled from the cylinder and the latter remains stationary although the gear revolves and conversely when the shaft 108 is forced outwardly axially of the cylinder, the latter is operatively connected to the gear, whereby rotation of the gear revolves the cylinder.

During the descent of the bed and form, the cylindrical half surface of the cylinder is in cooperative relation with the printing form and the printing operation occurs, but during the ascent of the bed and form, the cylinder remains stationary with its cut away or sunken face toward the form whereby no printing occurs during this period.

In front of the bed and cylinder, the press is equipped with a supply-pile board 21 carrying the stack 22 of sheets to be printed

and fed upwardly gradually by any of the well-known means, not shown, to compensate for the gradual depletion or reduction of the pile, the topmost sheets being removed individually in succession and delivered to an inclined, apertured, suction, registration feed-board 23 by suction-shoes 24, indirectly mounted on or carried by bent, hollow, rock-arms 25 fixed to an oscillatory, hollow shaft 26 through which and the supporting arms 25 suction is applied in any appropriate manner to the suction-shoes, the shaft being oscillated, and hence the suction-shoes carried back and forth, by a rotary shaft 27 connected to shaft 26 by a crank-arm 28 on the former shaft, an arm 29 fixed to the latter shaft, and an intervening or connecting link 31. Shaft 27 is driven from shaft 13 by a sprocket-wheel and chain connection 20.

Also in front of the bed are a pair of form-inking rollers 32 and 33 and their co-acting vibrator-roller 34, an ink-fountain 35, a distribution-drum 36, a pair of ductor-rollers 37 and 38, and distribution and transfer rollers 39.

To the rear of the bed, the printing-press has an automatically progressively descending delivery table or platform 41 actuated by means, not fully shown, and a sheet delivery mechanism mounted on a pair of rock-arms 42, only one of which is illustrated, fixed on a shaft 43 rocked in proper timed relation to the other movable parts of the mechanism by an arm 44 of the shaft 100 connected by a link 45 to a crank-arm 46 on shaft 13.

Fixedly mounted on the two spaced rock-arms 42, one at each side of the machine, is a shaft 47, (Figure 4), and rockingly mounted on the opposite ends of such shaft are a pair of bracket-arms 48, only one being illustrated, carrying a shaft 49 rockingly mounted therein, one at least of such bracket arms having on its outer side a roller 51 adapted to travel on the top edge of a stationary cam-bar 52.

These supporting bracket-arms and the parts which they carry are under the influence of one or more springs 53 encircling shaft 47 having one end fastened to the shaft, the other end being secured to one of the arms, whereby such arms and their associated elements tend to swing downwardly, which action, of course, is controlled by cam-bar 52.

A block or bar 54 secured to shaft 49 provides a bearing for a gripper-shaft 55, a coil-spring 56 tending to turn such shaft, encircling the latter and having its ends fastened to the shaft and block respectively.

Shaft 49 also has a plurality of yoke arms 57, only one of which is illustrated, fastened to it, the bifurcated apertured ends of which accommodate the gripper-shaft 55, 130

which may also have bearings at its ends in the bracket arms, such shaft between the spaced parts of the arms 57 having curved, sheet-gripper fingers 58 secured thereto, the free ends of such fingers being designed to cooperate with lugs or feet 59 projecting downwardly from those portions of yoke arms 57 beneath shaft 49.

In addition, shaft 55 has an arm 61 fixed thereto carrying an anti-friction roller 62 adapted to coact with a cam 63 on the corresponding end portion of the impression-cylinder 19.

At the extreme rear of the machine, another stationary cam or abutment 64 is provided with which roller 62 is designed to engage to open up the gripper fingers and release the printed sheet so that it may fall on the delivery-pile 65 on board 41.

20 The operation of the appliance takes place practically as follows:

Before the impression-cylinder has reached its stop position, the latter being illustrated in Figure 3, the delivery grippers, in traveling to the left, will have come to the end of their movement in that direction or to the reversal position shown in Figure 2, the feet 59 and the gripper-fingers being held in proper open relation for the 25 reception of the printed sheet from the cylinder by reason of the shape of cam 52 with which roller 51 coacts.

It will be clear that if the lugs 59 and their companion fingers 58, except for the slight rocking of the latter to grip or release the sheet, were rigid with their supporting and carrying arms 42, they would constantly change position with relation to the horizontal as the arms rocked about their center 43 of oscillation.

40 In other words, if these were properly arranged to deliver the sheet at the rear of the bed, they would not be in correct position to receive the sheet when adjacent to the impression-cylinder, and vice versa.

It is, therefore, desirable or necessary to rock these parts to compensate for the changing positions of their supporting arms. Such result is accomplished through 50 the action of the one or more springs 53, the controlling cam 52, and a stop pin and slot connections 66 and 67 between the bracket arms and their supporting shaft 47.

Cam 52 assures that these feet 59 will be 55 in proper vertical position as shown and at the correct elevation, and that the gripper fingers 58 will be in proper relation thereto to receive the sheet from the cylinder, whereas the stop pin 66 and the end of slot 67 insures the correct upright relation of 60 these feet when the arms 42 are in a wholly different position when the sheet is delivered by the opening of the gripper fingers.

When the delivery gripper fingers are in 65 the position shown in Figure 2, they are

held depressed or open by the cylinder cam or projection 63 engaging roller 62.

The delivery mechanism reverses and begins its travel to the right and by reason of the fact that it is actuated by a crank-arm 70 its movement is accelerated.

At the same time, the cylinder continues its clockwise rotation, as viewed in Figure 2, and, since it is now traveling faster than the accelerating delivery grippers, even 75 though it is in reality diminishing in speed, it not only catches up to the grippers to which it transfers the printed sheet, but continues for a moment to revolve faster than the grippers travel, thereby slightly 80 buckling the printed sheet wrapped around the cylinder and having a tendency to cling to it away from the latter hence facilitating its withdrawal or removal by the grippers which, by their acceleration, quickly strip 85 the sheet from the cylinder and carry it away above the bed which is now near its lower limit of travel.

Cam 63 holds the delivery gripper fingers open until the transfer has been completed, 90 and then, by reason of the increasing speed of the delivery mechanism and the gradually retarding speed of the cylinder, the roller 62 leaves the cam at the correct moment to grip the sheet, the cylinder grippers, of course, releasing the sheet at the proper moment for such transfer, which takes place before the cylinder stops, that is to say between the two positions of the cylinder shown in Figures 2 and 3. 95

The printed sheet is carried or conveyed over the depressed bed and form and above the delivery pile where, at the right moment, roller 62 strikes bar 64 opening the gripper fingers and freeing the sheet which 105 drops on to the printed sheet stack.

In such active or sheet conveying movement of the delivery mechanism, when roller 62 leaves the cam-bar 52, the spring or springs 53 rock the bracket-arms down as 110 far as the stops 66, 67 will permit, as shown in Figure 5, which is the correct relation of these elements when they reach the sheet discharging position illustrated in such figure. 115

It is merely essential that the gripping mechanism be in accurate position when receiving and discharging the sheet, its position in the interim being of little moment provided no extreme position is assumed, 120 which, of course, cannot occur in the device presented.

Thus the printed sheet is effectively and quickly stripped or removed from the cylinder, by reason of the buckling action specified, before the cylinder becomes stationary, which enables the delivery of the sheet over and without conflict with the vertically reciprocating bed. 125

The next or oncoming sheet, having been 130

fed to the transfer board 23, is by movement of the latter, accomplished by instrumentalities not shown, registered with suitable front and side guides or gauges and gripped to the cylinder while the latter is stationary by the automatic closing of the cylinder gripper fingers 40, whereupon at the proper instant the cylinder makes one complete revolution during which the printing function is accomplished and the printed sheet stripped off before the cylinder stops in the manner above indicated.

Those acquainted with this art will have no difficulty in understanding how the several objects of the invention have been accomplished in the mechanism illustrated and described, but, of course, the invention is not limited to the mechanical details of this appliance.

20 I claim:

1. In a printing-press, the combination of an impression-cylinder having a sheet receiving surface, means to rotate said cylinder intermittently, means to feed successive sheets to such same cylinder surface during its successive periods of rest, and delivery means to initiate the discharge of the sheets from such cylinder surface before its periods of rotation cease, substantially as described.

2. In a printing-press, the combination of an impression-cylinder having a sheet-receiving surface, means to rotate said cylinder intermittently, means to feed a sheet to such cylinder surface during each of its periods of rest, and delivery means to initiate the discharge of the sheets from such cylinder surface before its periods of rotation cease.

3. In a printing-press, the combination of an impression-cylinder, means to rotate said cylinder intermittently, means to feed sheets to the cylinder during its periods of rest, and delivery means to initiate the discharge of the sheets from the cylinder before its periods of rotation cease and traveling at the moment of sheet transfer at a speed different from that of the cylinder, substantially as described.

4. In a printing-press, the combination of an impression-cylinder, means to rotate said cylinder intermittently, means to feed sheets to the cylinder during its periods of rest, and delivery means to initiate the discharge of the sheets from the cylinder before its periods of rotation cease and traveling at the moment of sheet transfer at a speed less than that of the cylinder, substantially as described.

5. In a printing-press, the combination of a vertically-reciprocating printing-form bed, means to reciprocate said bed, an impression-cylinder cooperating with said form, means to rotate said cylinder intermittently, means to feed sheets to the cylinder during its pe-

riods of rest, and delivery means constructed to transport the printed sheets across the path of travel of the bed and to initiate their discharge from the cylinder before its periods of rotation cease, substantially as described.

6. In a printing-press, the combination of an impression-cylinder, means to rotate said cylinder intermittently at a variable speed, means to feed sheets to the cylinder during its periods of rest, and delivery means to initiate the discharge of the sheets from the cylinder during the periods of decrease in speed of the latter, substantially as described.

7. In a printing-press, the combination of an impression-cylinder, means to rotate said cylinder intermittently, means to feed sheets to the cylinder during its periods of rest, and delivery means operable at a variable speed and adapted to initiate the discharge of the sheets from the cylinder during the periods of speed increase of said delivery means, substantially as described.

8. In a printing-press, the combination of an impression-cylinder, means to rotate said cylinder intermittently at a variable speed, means to feed sheets to the cylinder during its periods of rest, and delivery means operable at a variable speed and adapted to initiate the discharge of the sheet from the cylinder during the periods of speed decrease in the latter and during the periods of speed increase of said delivery means, substantially as described.

9. In a printing-press, the combination of a vertically-reciprocating printing-form bed, means to reciprocate said bed, an impression-cylinder cooperating with said form, means to rotate said cylinder intermittently at a variable speed, means to feed sheets to the cylinder during its periods of rest, and delivery means operable at a variable speed and constructed to transport the printed sheets across the path of travel and above the bed and to initiate the discharge of the sheets from the cylinder during periods of simultaneous speed decrease of the cylinder and speed increase of the delivery means, the latter at the moment of sheet transfer traveling at a less speed than that of the cylinder, substantially as described.

10. In a printing-press, the combination of a form-carrier, means to operate said carrier, an impression-cylinder, means to operate said cylinder, a delivery mechanism, including means to grip the sheet and remove it from the cylinder, a mounting for said delivery mechanism, means to actuate said mounting, and means to rock said sheet gripping means on said mounting, substantially as described.

11. In a printing-press, the combination of a form carrier, means to operate said carrier, an impression-cylinder, means to oper-

ate said cylinder, delivery mechanism including means to grip the sheet and remove it from the cylinder, an oscillatory mounting for said delivery mechanism, means to rock 5 said mounting, and means to turn said sheet gripping means on said mounting, substantially as described.

12. In a printing-press, the combination of an impression-cylinder, means for removing 10 sheets therefrom, and means for buckling

the sheets thereon to facilitate their removal therefrom, substantially as described.

13. In a printing-press, the combination of an impression-cylinder, the normal operating speed of which varies between certain 15 limits, and means for feeding sheets thereto and removing the same therefrom under different speed conditions, substantially as described.

BURT D. STEVENS.
